UNITED STATES PATENT OFFICE

142,614

DESIGN FOR A SHUTTLECOCK OR SIMILAR ARTICLE

James L. Clark, Chicago, Ill.

Application June 16, 1945, Serial No. 120,156

Term of patent 14 years

(Cl. D34—5)

To all whom it may concern:

Be it known that I, James L. Clark, a citizen of the United States, residing in Chicago, Cook County, Illinois, have invented a new, original, and ornamental Design for a Shuttlecock or Similar Article, of which the following is a specification, reference being had to the accompanying drawing, forming a part hereof.

Figure 1 is a plan view of a shuttlecock or similar article embodying my new design; and

Figure 2 is an elevational view thereof.

I claim:

The ornamental design for a shuttlecock or similar article, substantially as shown.

JAMES L. CLARK.
